UNITED STATES PATENT OFFICE.

JOSEPH P. OSCHGER, OF CHICAGO, ILLINOIS.

HYDRAULIC ELEVATOR.

1,350,563.

Specification of Letters Patent. Patented Aug. 24, 1920.

Application filed June 18, 1918. Serial No. 240,621.

To all whom it may concern:

Be it known that I, JOSEPH P. OSCHGER, a citizen of the United States, residing at Chicago, in the county of Cook and State of Illinois, have invented a new and useful Improvement in Hydraulic Elevators, of which the following is a full, clear, and exact description, reference being had to the accompanying drawing, forming part of this specification, in which—

Figure 1 is a side elevation, partially in section, of one form of my invention, and

Fig. 2 is a detail sectional view of the cushioning apparatus and the valve therefor. This invention relates to an improvement in hydraulic elevators, and more particularly to the type of elevator-operating devices shown in Patent No. 1,116,615, issued to Charles E. Oschger on November 10, 1914.

The object of my invention is to provide an inexpensive and efficient valve system for controlling the flow of water to and from the cushioning apparatus, and in which the pressure for controlling the valve for the cushioning apparatus will vary in accordance with the pressure in the line or main water-supply tank.

The precise nature of my invention will be best understood by reference to the accompanying drawings, which will now be described, it being premised, however, that various changes may be made in the details of construction and the general arrangement of the parts without departing from the spirit and scope of my invention, as defined in the appended claims.

In the drawing, the reference character 2 designates the elevator car, 3 the plunger therefor, and 4 the hydraulic cylinder for the plunger, the apparatus being shown in this case as attached to a plunger elevator, although it may be employed with a horizontal cylinder elevator or a vertical cylinder elevator. 5 designates the controlling valve having an inlet port 6 connected to the usual pressure tank 7. 8 designates the exhaust port and 9 the port communicating with the valve 5, and which port is in direct communication with the pipe 10 connected to the cylinder 4. The stem 11 of the valve carries three valve disks 12, 13 and 14, so arranged that in one position of the valve there is a free connection between the ports 6 and 9, while the port 8 is closed. In its second position, the ports 8 and 9 are connected, while the port 6 is closed, and in a

third or intermediate position, both of said ports 6 and 8 are closed.

The pipe 10 leading to the cylinder 4 is provided with a branch 15 which is in communication with a cushioning reservoir 16, and intermediate of the cushioning reservoir 16 and the pipe 10 is a gate valve 17 for cutting off communication between the pipe 10 and the cushioning reservoir.

The cushioning reservoir is more clearly shown in Fig. 2 and comprises a casing 18 which is mounted directly on the top of the flange of the pipe 15. Mounted within this casing 18 is a sleeve 19 having ports 20 through the walls thereof. This sleeve 19 has a threaded connection with the lower end of the casing 18. Mounted on the upper portion of the sleeve 19 is a shell 21. The lower portion of the shell 21 and the sleeve 19 are arranged to form cylinders for the pistons 22 and 23, respectively, and 22^a designates a stop for the piston 22, which is arranged to limit the downward movement thereof. These pistons are provided with cup-shaped washers to form tight joints between the pistons and the cylinders to restrict the flow of fluid from the casing 18 to the branch pipe 15. Connected to the upper and lower portions of the casing 18 is a water gage glass 24 for noting the height of the column of water within said casing. In the upper portion of the shell 21 is formed a large air chamber which is in direct communication by means of a pipe 25 with the air space of the pressure tank 7, so that by this arrangement, the top of the piston 22 is acted upon by the air pressure from the tank 7, while the bottom of the piston 23 is at times under the pressure of the water from said pressure tank which passes through the port 6 when the elevator is moving upwardly.

Extending from the lower part of the casing 18 to the branch pipe 15 is a connection 31, having a check valve therein to permit fluid to flow from the casing 18 to the branch pipe 15, but to prevent the flow of fluid from the branch pipe to the casing 18. This valve is held to its seat by a spring 32 surrounding the stem 33 of the valve, and is arranged to be adjusted to vary the tension in any desired manner or in a manner shown in the Patent No. 1,116,615. Communicating with the connection 31 is a drain-pipe 26 which leads to a discharge tank 27, and 28 is a valve in said line for

cutting off the flow from the casing 18 to the tank 27. 29 is a valve in the pipe 25 for cutting off communication between the shell 21 and the pressure tank, while 30 5 designates a pet cock in the top of the casing 18 for relieving the pressure therein, if desired.

The operation of the device is as follows:

With the parts in the positions shown, 10 water is passing from the main pressure tank through the ports 6 and 9 to the pipe 10 so that the elevator is moving upward. If the operator should quickly draw the valve stem upwardly to bring the valve 15 disks 13 and 14 on opposite sides of the port 9, the flow of water from the pressure tank to the pipe 10 would suddenly be stopped. This sudden movement of the valve would cause the car to come to a stop with a jar, 20 unless cushioning means were provided, as the car could not move upward under its momentum, without causing a partial vacuum in the cylinder 4. If the valves are suddenly moved to the position just described, the car would not come to a sudden 25 stop, as water would be drawn from the casing 18 through the connection 31. By means of this arrangement, no vacuum would be formed in the cylinder 4 as water 30 is drawn from the casing 18.

Assuming now that the car was moving down, the water passing from the cylinder out through the port 8 and the valve is suddenly moved so that the disks 13 and 14 are 35 on opposite sides of the port 9. This sudden movement of the valve will cut off the flow of fluid from the pipe 10 to the port 8, the back pressure in the pipe 10 would be forced through the pipe 15 and move the 40 pistons 22 and 23 upwardly against the pressure in the main tank, the excess water passing through the ports 20 into the casing 18, so that the elevator would be brought to a stop gradually. As the piston 22 is always 45 under line pressure through pipe 25, the relief valve formed of the pistons 22 and 23 will be returned to the position shown in the drawings as soon as the car has come to rest.

50 If by reason of leakage or other causes, the volume of air in the upper part of the casing 18 becomes too greatly reduced, the valve 17 can be closed and the valves 28 and 30 opened to permit fluid to pass from the 55 casing 18 to the tank 27 and admit air to the casing 18.

The advantages of my invention result from the provision of a valve system for a cushioning apparatus, in which the valve is 60 under the control of the pressure in the main supply tank, so that no adjustments need be made for varying pressure.

I claim:

1. In a hydraulic elevator, a pressure 65 tank, an actuating cylinder, a supply and

outlet pipe leading thereto, a controlling valve for said pipe, a cushioning reservoir connected to a branch of said pipe, a valve in said connection, an air chamber above said valve, and connections between said air chamber and the pressure tank for the elevator, substantially as described. 70

2. In a hydraulic elevator, a cylinder, a pressure tank containing air and water, a controlling valve, connections leading from said controlling valve, to the cylinder and to the pressure tank, an exhaust from said controlling valve, a cushioning reservoir comprising a chamber containing air and water, operative connections between the lower end of said cushioning reservoir and the connection leading from the valve to the cylinder, a valve for controlling the flow of fluid from said pipe to the cushioning reservoir, an air chamber above the valve, and a connection extending from said air chamber to the air space of the pressure tank, substantially as described. 75

3. A motor cushioning device for hydraulic elevators, comprising a pressure tank, 90 means for supplying operating fluid to the motor from said tank, an air cushioning chamber operatively connected with said motor, means for supplying air to said cushioning chamber from said pressure tank, and means for compressing the air in said chamber when the descent of the elevator is stopped, substantially as described. 95

4. A motor cushioning device for hydraulic elevators, comprising a pressure tank, 100 means for supplying operating fluid to the motor from said tank, an air cushioning chamber, a piston therein, means for supplying air to said chamber from the pressure tank at one side of the piston, and an operative connection between the chamber at the other side of the piston and the motor for moving the piston to compress the air in said chamber when the descent of the elevator is stopped, substantially as described. 105

5. In a hydraulic elevator, a motor, a pressure tank, means for supplying operating fluid to the motor from said tank, a cushioning reservoir comprising air and water chambers, an operative connection between 115 said air chamber and the pressure tank, and an operative connection between said chambers and the motor, substantially as described.

6. In a hydraulic elevator, a motor, a pressure tank, means for supplying operating fluid to the motor from said tank, a cushioning reservoir comprising air and water chambers, a piston in said reservoir subjected to the pressure in the air chamber, means for 125 maintaining a pressure in the air chamber substantially equal to the pressure in said tank, and an operative connection between said chambers and the motor, substantially as described. 130

7. In a hydraulic elevator, a motor, a pressure tank, means for supplying operating fluid to the motor from said tank, a cushioning reservoir having an operative connection with the motor and an operative connection with said pressure tank, substantially as described.
8. In a hydraulic elevator, a pressure tank having air and water therein, a motor, means for supplying the motor with operating fluid from the tank, a control valve for said supply, a cushioning reservoir, a piston valve for said reservoir, an operative connection between said control valve and said reservoir for subjecting one end of the piston valve directly to the action of the operating fluid, and a second connection between the reservoir and the upper end of the pressure tank for subjecting the other end of the piston valve directly to the action of the air pressure in the tank, substantially as described.
9. In a hydraulic elevator, a pressure tank having air and water therein, a cushioning reservoir having a separate air chamber, connections between one end of the cushioning reservoir and the lower portion of the pressure tank, a relief valve below said air chamber and connections from said air chamber to the upper portion of the pressure tank, substantially as described.
10. A device for preventing jarring of elevator on the stop thereof, comprising a hydraulic motor, a pressure tank supplying operating fluid to said motor, a cushioning reservoir having a piston therein, an operative connection between said reservoir and said motor, and a connection between said reservoir above said piston and the pressure tank for subjecting the piston to the pressure in said tank, substantially as described.

In testimony whereof I have hereunto set my hand.

JOSEPH P. OSCHGER.
